UNITED STATES PATENT OFFICE

GEORGE E. TILLER, OF SIOUX CITY, IOWA

OIL BURNER

Application filed October 22, 1928. Serial No. 314,267.

My invention relates to oil burners of the type patented in Letters Patent #1,529,821 to Myron W. Wood.

I am the assignee of said patent and my present invention has for its object to improve upon the structure disclosed in said patent.

More specifically, it is my purpose to improve upon the vaporizing portion of the structure, whereby the cost of fuel may be reduced approximately 10% over that of existing types of burners.

A further object is to provide a burner having the flame dividing lugs of the before mentioned application, the flange which carries said lugs being divided so as to facilitate the assembling of the burners in a furnace and the lugs of the outer portion of the flange serving not only in their flame dividing capacity but also as a means for supporting the outer portion of the flange upon the inner portion thereof.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a vertical, transverse, central, sectional view through the burner of the present invention.

Fig. 2 is a plan view of the same, a part of the flame spreading hood being removed to disclose the construction therebeneath.

Fig. 3 is an enlargement of a portion of Fig. 1.

I have used the reference character 10 to indicate generally the skirt or flue upon which the burner is supported and which serves to provide a closed draft through the grates of a furnace to the burner proper.

The latter includes an outer, cylindrical wall 11, having a slightly reduced neck 12 at its lower extremity, forming a shoulder 13 to seat upon the skirt 10. An intermediate wall 14 is formed integrally with the wall 11 and connected thereto by a bottom wall 15, which extends inwardly beyond the wall 14 and thence upwardly as at 16 to form an over-

flow well 17. The space between the walls 11 and 14 forms the vaporizing well 18.

A flame directing flange 19 is formed integrally with the wall 11 and extends upwardly and outwardly from the upper extremity 55 thereof, above the top of the wall 14, whereby overflow oil will pass over the wall 14 into the overflow well 17.

Flame spreading lugs 21 are formed integrally with the flange 19.

An air spreading hood 21 extends into the space encircled by the wall 14 and over and beyond the wall 14 to about the position shown in Fig. 3. Three vertical fins 22, formed integrally with the hood 21, are shouldered, 65 as at 23, to rest upon and within the wall 16.

The parts just described are substantially the same as in the prior patent hereinbefore referred to.

I find that by leaving the well open above 70 the liquid, that a greater percentage of vaporization will take place within the well itself. The heat from the flame is carried by conduction through the wall 11 to the walls of the well 18 and vaporization will take place within the well, the gases rising to the top of the well to be burned. I find that a more perfect flame is obtained where the top of the well is covered by a ring such as the ring 24 provided with burner openings 25. The ring 24 80 is inclined at about the same angle as the flange 19 and is provided with a substantially horizontal flange 26, which rests within an annular seat 27, formed in the wall 11. The upper surface of the ring 24 is substantially flush with the upper surface of the flange 19.

The ring is thickened between the walls 14 and 11 so as to form a shoulder 28 which fits snugly against the inner surface of the wall 11. The inner extremity of the ring is provided with a vertical flange 29, which receives the wall 14 and is sealed thereagainst by means of cement 30. The seating of the shoulder 28 and the flange 27 effectively seals the well against the escape of gas except 90 through the openings 25 without interfering with the expansion of the parts relative to each other.

The gas will therefore issue through the openings 25 and be burned above the burner 100

ring in a flame which spreads outwardly and upwardly over the flanges 19. The air current directed downwardly against the ring by the hood 21 instead of being broken up by the wall 11, is deflected against the smooth surface of the ring into a smoothly flowing, expanding ring of moving air currents and flame. With the upper extremity of the well uncovered, there is a tendency to produce eddy currents interfering with the smooth action of the burner. The smooth flowing of the air currents results in more perfect combustion and higher efficiency of operation.

The vaporization within the well 18 is greatly enhanced by the use of a relatively tightly woven wick 31 in the form of a cylindrical sleeve encircling the wall 14 and fitting snugly thereagainst. The wick takes up only a small portion of the space of the well. It rests at its lower end upon the bottom wall 15 and at its upper end within the space between the flange 29 and the wall 14.

The wick 31 serves to carry the oil from the bottom of the well 18 upwardly against the heated wall 14 and provides a large surface for radiation of the vaporized oil into the surrounding space.

A continuation of the flange 19 is formed by the flame spreading ring 32, supported upon the flange 19 by the projecting ends of the lugs 33 and inclined at substantially the same angle. The lugs 33 serve the double function of giving the proper flame division and of supporting the ring 32 in such relation to the remainder of the burner that it can be lifted from the burner at any time. This facilitates installation of the burner and removal of the burner for cleaning or repairs.

I find that the flame dividing quality of the lugs 20 is greatly enhanced by the use of an auxiliary set of lugs, staggered relative to the inner seat.

The feed pipe 34 and overflow pipe 35, communicating with the overflow chamber, are shown in Fig. 1. These parts are the same as in the prior inventions hereinbefore mentioned.

Some changes may be made in the construction and arrangement of the parts of my invention without departing from the real spirit and purpose of my invention and it is my intention to cover by my claims, any modified forms of structure or use of mechanical equivalents, which may be reasonably included within their scope.

I claim as my invention:

1. An oil burner of the type having concentric, spaced walls, connected at their lower extremities to form an annular well, a feed pipe communicating with said well, a burner ring closing the top of said well, and provided with openings for the escape of gas, said ring having a substantially horizontal flange resting upon the outer wall and a vertical, inner flange receiving the inner wall, and a cylindrical wick encircling the inner wall and spaced from the outer wall, extending from near the bottom of the well, and received between the vertical flange of the burner ring and the inner wall.

2. An oil burner of the type having concentric, spaced walls, connected at their lower extremities to form an annular well, a feed pipe communicating with said well, a burner ring closing the top of said well, and provided with openings for the escape of gas, and a cylindrical wick encircling the inner wall and spaced from the outer wall, extending from near the bottom of the well to the burner ring and disposed entirely below the upper surface of said ring.

3. An oil burner of the type having concentric, spaced walls, connected at their lower extremities to form an annular well, a feed pipe communicating with said well, an air spreading hood extending into the space within the inner wall, and over the well, a burner ring closing the top of said well and providing openings for the escape of gas, and a wick encircling the inner wall, substantially in contact therewith, and spaced from the outer wall to provide a vaporization chamber in communication with the burner openings, whereby to receive oil from the bottom of the well, and carry it upwardly, vaporizing it by heat from said inner wall, said wick extending vertically substantially the entire height of the inner wall.

4. An oil burner of the type having concentric, spaced walls, connected at their lower extremities to form an annular well, a feed pipe communicating with said well at its lower extremity, a burner ring closing the top of said well, and provided with openings for the escape of gas, an air spreading hood extending into the space within the inner wall, and over the well, and a flame spreading flange extending outwardly from the upper extremity of the outer wall, the upper surface of the burner ring being substantially flush with the upper surface of said flange.

5. An oil burner of the type having concentric, spaced walls, connected at their lower extremities to form an annular well, a feed pipe communicating with said well at its lower extremity, an air spreading hood extending into the space within the inner wall and over the well, a flame spreading flange extending outwardly from the upper extremity of the outer wall and a flame spreading ring having radial flame dividing lugs projecting beyond the inner edge thereof, and seated upon said flame spreading flange.

6. An oil burner of the type having concentric, spaced walls, connected at their lower extremities to form an annular well, a feed pipe communicating with said well, a burner ring closing the top of said well, and provided with openings for the escape of gas, and a cylindrical wick encircling the inner wall and

1,756,226

spaced from the outer wall, to form a vaporization chamber in communication with the burner ring openings, said wick extending from near the bottom of the well to the burner ring.

5 - Signed this 29 day of September, 1928, in
the county of Woodbury and State of Iowa.
GEORGE E. TILLER.
